Daniel F. Owens.

UNITED STATES PATENT OFFICE

2,195,540

WALL HANGER FOR RADIATORS

Daniel F. Owens, Buffalo, N. Y.

Application November 16, 1938, Serial No. 240,757

3 Claims. (Cl. 248—234)

My invention relates to improvements in wall hangers for steam or hot water radiators and the like, and the object of the invention is to provide a hanger construction which is capable of being readily adjusted to fit any size of radiator and which is also capable of adjustment to permit the radiator to be hung level in all respects irrespective of any irregularities of the wall surface upon which the radiator is positioned.

In standard radiator hanging constructions adjustments of height only can be made, and therefore because of irregularity of wall construction, the radiators when hung frequently project out of line either at the top or bottom whereby the proper circulation of fluid within the radiator is often impaired and the general appearance of the radiator made offensive to the critical eye.

Another object of my invention is to provide a hanger of extremely simple construction which can be very readily adjusted and secured to the wall by a minimum number of attachment points.

With these and other objects in view as shall hereinafter appear, my invention consists of a radiator hanger constructed and arranged all as hereinafter more particularly described and illustrated in the accompanying drawing in which:

Figure 1 is a perspective view of my radiator hanger assembly.

Figure 2 is a vertical cross-sectional view through a radiator and showing it supported by my hanger which is in turn secured to a wall.

Figure 3 is a plan view of a fragmentary portion of a hung radiator as illustrated in Figure 2, and,

Figure 4 is an enlarged perspective view of an eye-bolt and retaining button as used in my hanger assembly.

Like characters of reference indicate corresponding parts in the different views of the drawings.

While my drawing illustrates a single hanger assembly supporting a fragmentary portion of a radiator, it is to be understood that in most cases at least two hangers are used for one radiator. The hangers are positioned in spaced apart relation. As the hanger assemblies are each of the same construction, it is only necessary for me to describe the construction and application of a single hanger assembly as illustrated in the drawing.

The wall engaging portions of the assembly consist of a pair of upper and lower angle mem-

bers 1 between which extends a vertical spacing rod member 12. The upper portion 11 of the rod member 12 is of reduced diameter and threaded to receive a supporting nut 3 on its upper end. The lower end of the rod 12 is furnished with a reduced portion 13 inserted into an orifice in the horizontal plate of the lower angle member 1 and a cotter pin 13a or the like is provided in this reduced portion and below the angle member to hold the latter in suspended engagement with the rod for movement therewith during its adjusting movements. In this connection this angle member abuts the wall from which the radiator is hung and is free to slide over the wall during adjustments. The unthreaded portion of the rod member 12 is formed intermediately of its height with a pair of bosses 14 between which is pivoted the upper end of a hook member 4. The lower hook portion of the member 4 engages the bottom of the connecting nipple or nipples 15 between the radiator sections 2, as illustrated in Figure 2. The rod member 12 is rotatable within the angle members 1, so that the hook member 4 can be swung for insertion between radiator sections, if so desired.

The upper angle member 1 is secured in place to the wall surface by a nut and stud 16, the stud projecting from the wall in the usual manner and passing through a horizontal slot 5 in the vertical portion of the upper angle member 1, the nut on the stud bearing against the face of the vertical portion of the angle member 1. The slot 5 is of sufficient length to permit the upper angle member 1 being slid or tilted into any desired position in aligning the radiator in place. The upper end 11 of the threaded rod extends through an orifice in the horizontal portion of the upper angle member 1, and the upper portion of such threaded rod projecting above the orifice carries the ring eye 17 of an eye-bolt 8. The eye-bolt 8 extends forwardly from the upper angle member 1 and between the same pair of radiator sections as the hook member 4. The outer end of the eye-bolt 8 is threaded to receive a retaining nut 9 and also freely receives a retaining button 10 which is shaped to fit snugly between the sections and bear against such sections under the pressure of the nut 9, as illustrated in Figure 3.

It not infrequently occurs that because of slight irregularities of wall construction the upper or lower extremities of radiators, after being hung, project so that the radiator is out of true vertical alignment, thereby impairing its appearance and efficiency. To obviate this difficulty,

I provide sliding spacing plates 6 which are secured to the horizontal portions of the upper and lower angle members 1. Each of the plates 6 is formed with a pair of parallel slots 7 to receive a pair of bolts 18 projecting downwardly from the horizontal portions of the angle members 1, and also central open ended slots 20 whereby the plates can slide past the rod member 12. The bolts 18 carry nuts 19 and such nuts bear against the lower faces of the plates 6 and thus secure the plates 6 against the horizontal portions of the angle members 1 in any adjusted positions. The plates 6 at the lower extremity of rod member 12 contain suitable notches 22 adapted to receive the hook member 4 so that the outer faces of plates 6 will bear evenly at all times against the inner surfaces of the radiator when suspended and adjusted.

The outer edges of the plates 6 bear against the inner back edges of at least two of the radiator sections, and thus when the radiator is hung and before the nut 9 on the eye-bolt 8 is finally tightened up, the plates 6 can be slid to or fro relatively to the angle members 1 and thus either the top or bottom of the radiator can be moved inwardly or outwardly to effect a vertical position of the radiator. When the radiator is in the desired vertical adjustment with the outer edges of the plates 6 bearing against the inner back edges of the radiator sections, the nuts 19 on the bolts 18 are tightened to lock the plates 6 in place and the nut 9 on the eye-bolt 8 is tightened up to draw the retaining button 10 firmly in place and in turn the radiator tightly against the plate 6. If the threaded end of the eye-bolt 8 projects outwardly from the nut 9 an objectionable distance after the radiator is secured in place, such projecting end of the rod can be conveniently cut off.

In order to lift or lower the radiator to insure it being in a true horizontal position, the nut 3 can be moved either upwardly or downwardly on the threaded rod 11 whereby the rod and the lower angle member 1 suspended therefrom are either raised or lowered in respect to the upper angle member 1 with a consequent raising or lowering of the hook member 4 and the end of the radiator supported by such hook. If it is desired to attach the upper angle member 1 to a wooden surface, such attachment can be made by inserting suitable screws through the orifices 21 in the vertical portion of the upper angle member.

From the foregoing description it will be apparent that I have devised a very simple and yet efficient hanger for radiators whereby the radiator can be readily aligned in place, and furthermore my device is so constructed that it can be used with any standard type of radiator irrespective of the height of the sections or length of the unit, and although I have shown and described a particular embodiment of my invention, it is to be understood that I can make any such changes and alterations as I may from time to

time deem necessary without departing from the spirit of my invention as set forth in the appended claims.

What I claim as my invention is:

1. In a radiator hanger of the character described, a pair of upper and lower wall engaging members, an adjustable upright rod disposed between such members, a hook-like member extending downwardly from said rod for engaging and supporting the bottom of the radiator, a bolt extending outwardly from the upper wall engaging member through the radiator sections, means on the bolt for engaging and retaining the upper portion of the radiator against outward movement, and a pair of spacing elements adjustably secured to the upper and lower wall engaging members, said elements engaging and retaining the rear face of the radiator in spaced relation to the upper and lower wall engaging members. 20

2. In a radiator hanger of the character described, a pair of upper and lower wall engaging members, one being fixed to the wall and the other being free to move relatively thereto, an adjustable upright rod disposed between such members, a hook-like member extending downwardly from the spacing rod for engaging and supporting the bottom of the radiator, a bolt extending outwardly from the upper wall engaging member through the radiator sections, means on the bolt for engaging and retaining the upper portion of the radiator against outward movement, and a pair of spacing plates slidably secured to the upper and lower wall engaging members, each of the plates engaging at least two sections of the radiator and retaining the radiator in spaced relation to the upper and lower wall engaging members. 30

3. In a radiator hanger of the character described, a pair of upper and lower wall engaging angle members, one of said members being fixed and the other being free to move relatively to the wall, an upright rod extending between the horizontal portions of the angle members and adjustably connected at its upper end to said fixed wall member and coupled at its lower end to the movable wall member, a hook-like member pivotally suspended from said rod intermediate its ends for engaging and supporting the bottom of the radiator, a bolt extending outwardly from the upper wall engaging angle member through the radiator sections, means on the bolt for engaging and retaining the upper portion of the radiator against outward movement, a pair of spacing plates adjustably secured to the horizontal portions of the angle members, and bolts extending through orifices in the horizontal portions of the wall engaging angle members and through slots in the spacing plates, the outer edges of the plates engaging and retaining the rear face of the radiator in spaced relation to the upper and lower wall engaging members. 40
